R. O. GILBURG.
FILING MACHINE.
APPLICATION FILED JAN. 24, 1917.

1,249,741.

Patented Dec. 11, 1917.

UNITED STATES PATENT OFFICE.

ROY O. GILBURG, OF KALAMAZOO, MICHIGAN.

FILING-MACHINE.

1,249,741.

Specification of Letters Patent. Patented Dec. 11, 1917.

Application filed January 24, 1917. Serial No. 144,287.

To all whom it may concern:

Be it known that I, Roy O. GILBURG, a citizen of the United States, residing at the city and county of Kalamazoo, State of Michigan, have invented certain new and useful Improvements in Filing-Machines, of which the following is a specification.

This invention relates to improvements in filing machines.

10 My improved filing machine is especially designed by me as an attachment to a drill press or other machine tool, and the embodiment illustrated herein is adapted for that purpose.

15 The main objects of this invention are:

First, to provide an improved filing machine.

Second, to provide an improved filing machine adapted as an attachment for machine 20 tools.

Third, to provide an improved filing machine which is comparatively simple and economical in structure and is at the same time efficient in use.

25 Further objects, and objects relating to structural details, will definitely appear from the detailed description to follow.

I accomplish the objects of my invention by the devices and means described in the 30 following specification. The invention is clearly defined and pointed out in the claims.

A structure which is a preferred embodiment of my invention is clearly illustrated 35 in the accompanying drawing, forming a part of this specification, in which:

Figure I is a perspective view of my improved filing machine, a portion of the work table being broken away to better illustrate 40 the parts, the driving spindle being shown in one position by dotted lines.

Fig. II is a vertical longitudinal section on line corresponding to line 2—2 of Fig. I.

Fig. III is an enlarged detail section 45 through the supports for the adjustable table, on a line corresponding to line 3—3 of Fig. I.

Fig. IV is a detail section on a line corresponding to line 4—4 of Fig. I through the 50 file holder chuck.

Fig. V is an enlarged detail section on a line corresponding to line 5—5 of Figs. I and II, showing details of the connections to the file holder.

55 In the drawing similar reference characters refer to similar parts throughout the

several views, and the sectional views are taken looking in the direction of the little arrows at the ends of the section lines.

Referring to the drawing, I provide a 60 frame designated generally by the numeral 1, having a base 2 adapted to be mounted on the bed of a drill press or other machine tool in position to be driven by the spindle of such machine. The work table 3 is provided 65 with a pair of spaced arms 4 slotted longitudinally at 5 to receive the supporting bolt 6. This bolt is provided with a winged nut 7 by means of which the bolt may be clamped up to support the table in its ad- 70 justed positions, it being adjustable vertically and also being capable of tilting adjustment.

The frame is provided with an opening 8 at one end providing in effect an upright 9. 75 A way is provided for the reciprocating file holder 10, the way comprising a channel-like portion 11 formed in the upright 9 and a face plate 12 secured thereto by screws 13. The rear wall of this way is longitudinally 80 slotted at 14 to receive the pitman pin 15. A driving shaft 16 is journaled in the frame and provided at its inner end with the crank 17 which has a counterbalance 18. The pitman 19 is connected to the crank by the 85 wrist pin 20. At its outer end the shaft 16 is provided with a beveled gear 21 meshing with a beveled gear 22 on the driving spindle 23. This driving spindle is adapted to be received by the chuck of a drill press or 90 other machine tool.

To adapt the machine to different types of machine tools the spindle 23 is mounted in an adjustable support 24. This support is pivoted upon the shaft 16 and detachably 95 secured to the frame by the bolt 25. The lower end of the support is slotted at 26 and adjusted to the shaft by means of the screw 27. The support is not clamped upon the shaft but is adjusted thereto to provide 100 a suitable bearing fit.

The file 28 is secured in the tool holder, which is provided with a suitable chuck to receive the same, by means of the set screw 29. Any suitable form of chuck may be 105 employed in this relation.

With the parts arranged as I have illustrated and described, the machine may be readily adjusted to a drill press or other machine tool without any disorganization or 110 reorganization of such machine, and as it may be quickly attached or detached it does

not interfere with the general use of such machine. The work table or work holder shown I find to be very satisfactory but other forms may be employed as occasion requires.

5 I have not attempted to describe certain modifications and embodiments which I contemplate and which are included in the scope of the following claims, as I believe 10 the disclosure made will enable those skilled in the art to which my invention relates to embody or adapt the same as conditions may require.

Having thus described my invention, 15 what I claim as new and desire to secure by Letters Patent, is:

1. In a structure of the class described, 20 the combination of a frame, a work table mounted on said frame for adjustment, a file holder, a slide way in which said file holder is mounted to reciprocate below said table, said table having an opening through which a file arranged in said holder projects, a driving shaft journaled in said 25 frame, a counterbalanced crank on the inner end of said shaft, a pitman connecting said crank to said file holder, a driving spindle, a supporting bracket for said driving spindle pivotally mounted on said shaft and 30 detachably secured to said frame, and meshing beveled gears on said spindle and shaft.

2. In a structure of the class described, 35 the combination of a frame, a work table mounted on said frame for adjustment, a file holder, a slide way in which said file holder is mounted to reciprocate below said table, said table having an opening through which a file arranged in said holder projects, a driving shaft journaled in said 40 frame, a counterbalanced crank on the inner end of said shaft, a pitman connecting said crank to said file holder, a driving spindle

geared to said driving shaft, and an adjustable support therefor pivotally mounted to rotate about an axis concentric with the 45 axis of said driving shaft.

3. In a structure of the class described, 50 the combination of a frame, a work table mounted on said frame for adjustment, a file holder, a slide way in which said file 55 holder is mounted to reciprocate below said table, said table having an opening through which a file arranged in said holder projects, a driving shaft journaled in said frame, a counterbalanced crank on the inner end of said shaft, a pitman connecting said crank to said file holder, and a driving spindle geared to said driving shaft, and adjustable about the axis thereof.

4. In a structure of the class described, 60 the combination of a frame, a reciprocating file holder, a driving shaft journaled in said frame, a crank on the inner end of said shaft, a pitman connecting said crank to 65 said file holder, a driving spindle, a supporting bracket for said driving spindle pivotally mounted on said shaft and detachably secured to said frame, and meshing beveled gears on said spindle and shaft.

5. In a structure of the class described, 70 the combination of a frame, a reciprocating file holder, a driving shaft journaled in said frame, a crank on the inner end of said shaft, a pitman connecting said crank to 75 said file holder, a driving spindle geared to said shaft, and a support for said driving spindle, adjustable about the axis thereof.

In witness whereof, I have hereunto set my hand and seal in the presence of two witnesses.

ROY O. GILBURG. [L.S.]
